(74) Attorney, Agent, or Firm — Arch & Lake LLP

(22) Filed: **Sep. 2, 2022**

(57) **CLAIM**

(80) **Hague Agreement Data**

The ornamental design for a head-wearing camera, as shown and described.

Int. Filing Date: **Sep. 2, 2022**

DESCRIPTION

Int. Reg. No.: **DM/223251**

2. Head-wearing camera

Int. Reg. Date: **Sep. 2, 2022**

2.1: Front

Int. Reg. Pub. Date: **Sep. 16, 2022**

2.2: Back

(30) **Foreign Application Priority Data**

2.3: Left

Mar. 3, 2022 (CN) 202230106377.0

2.4: Right

(51) LOC (14) Cl. **16-01**

2.5: Top

(52) U.S. Cl.

2.6: Bottom

USPC **D16/309; D16/208**

2.7: Perspective

CPC ..... **G02C 11/10 (2013.01)**

2.8: Perspective

(58) **Field of Classification Search**

(Continued)

USPC D16/300, 309, 313, 314, 315, 320, 321,
D16/325, 326, 200, 208

CPC H04N 23/51; H04N 7/185; H04N 7/147;

H04N 7/188; H04N 23/611; H04N 7/155;

2.1 is a front view of a head-wearing camera with eyeglass, **2.2** is a back view thereof, **2.3** is a left view thereof, **2.4** is a right view thereof, **2.5** is a top view thereof, **2.6** is a bottom view thereof, **2.7** and **2.8** are two perspective views thereof.
